UNITED STATES PATENT OFFICE.

ALLEN P. LORD, OF NORTH WARREN, PENNSYLVANIA, ASSIGNOR OF ONE-HALF TO O. P. DUNN, OF NORTH WARREN, PENNSYLVANIA.

TROLLEY.

SPECIFICATION forming part of Letters Patent No. 736,855, dated August 18, 1903.

Application filed January 12, 1903. Serial No. 138,690. (No model)

To all whom it may concern:

Be it known that I, ALLEN P. LORD, a citizen of the United States, residing at North Warren, in the county of Warren and State 5 of Pennsylvania, have invented new and useful Improvements in Trolleys, of which the following is a specification.

This invention relates to trolleys; and it consists in certain improvements in the construction thereof, as will be hereinafter fully described, and pointed out in the claims.

Among the objects of the invention may be stated the protection of the edges of the trolley-wheel from injury through impact with the 15 wire or other obstruction, a finder for carrying the wire to the trolley, comprising peculiar improvements, as will appear more fully from the specification and claims; and the providing of the trolley with a harp which will 20 readily free itself from wires as it is drawn to place.

The invention is illustrated in the accompanying drawings as follows:

Figure 1 shows a front elevation, partly in 25 section, of the harp and trolley; Fig. 2, a side elevation; Fig. 3, an elevation showing a trolley-wire in its port.

A marks the trolley-wheel. It is journaled on a rod B. The rod B is secured in sockets 30 c' in the sides of the harp C. The harp is formed by splitting a pipe forming a part of the pole and bending the sides so that at no place do they form a right angle, a sufficient slant being given to the sides to prevent their 35 catching wires or other obstructions as the pole is being drawn down past them. The sockets c are kept in proper position to hold the rod B by means of the contracting device comprising the rods c' and turnbuckle. By 40 using this means of fastening the edges of the harp are free from all obstructions for the purpose herein described.

Arranged at each side of the trolley-wheel are the guards d. These are formed of disks 45 of metal, the edges overlapping the trolley-wheel in position to receive the impact where the trolley meets any obstruction rather than the edges of the trolley-wheel. In this way the edges of the trolley-wheel remain true, 50 and the trolley-wheel will run much more

freely than in the battered condition it is apt to reach when used as ordinarily. I prefer to secure these guards to the finder-spool D.

The finder-spool D are journaled on the rod B and are free to turn independently of the trolley A and of each other. They are provided with a spiral, which leads to the trolley-wheel. The guard d is cut away at d' to permit the wire to pass by the guard to the trolley-wheel. At the outer end of each spool 60 is a continuous groove d², which prevents the wire from leaving the spool should the trolley be moved in a backward direction. I prefer that the spiral flare abruptly near the trolley in order that the spools may clear the supports E, with which the trolley-wire e is usually carried. I prefer to make these spools of aluminium in that there is a tendency of the finder to spark, and I find that aluminium does not burn out as readily as other metals. 70

What I claim as new is—

1. The combination with the trolley-wheel A; of the guards d formed of harder metal than the trolley-wheel, said guards being supported independently of the trolley-wheel and 75 extending over the edges of the wheel.

2. The combination of a trolley pole and wheel; of a supporting-harp having unobstructed surfaces along its outer edges, the entire sides of the harp extending in directions less than at right angles to the pole; and a contracting device arranged between the sides of the harp. 80

3. The combination with a trolley pole and wheel; of a supporting-harp formed of a split 85 piece of tubing, the sides extending at less than a right angle to the pole.

4. The combination with a trolley pole and wheel; of a supporting-harp formed of a split piece of tubing, the sides extending at less 90 than a right angle to the pole; and a contracting device between the sides of the harp.

In testimony whereof I have hereunto set my hand in the presence of two subscribing witnesses.

ALLEN P. LORD.
